STRAIGHTENING APPARATUS FOR STRIP MATERIAL

Charles Patrick Naegeli, Long Island City, N. Y., assignor to General Motors Corporation, Detroit, Mich., a corporation of Delaware

Application March 30, 1944, Serial No. 528,746

11 Claims. (Cl. 140—148)

This invention relates to straightening apparatus for strip material, especially wire for heading machines, and comprises all of the features of novelty herein disclosed. Ordinarily, when it is desired to straighten wire in connection with a heading machine, a roll type wire straightener is fixed in position and the pulling of the wire through the straightening rolls is effected by the driven feed rolls on the heading machine. The varying amount of power necessary at the feed rolls to pull the wire through the straightener, due to differences in bends, kinks, etc. is apt to cause variables in the length of wire fed into the header for the shaping of the work pieces and hence the work pieces are not uniform. This extra, variable load on the header feed rolls is especially heavy and undesirable when the wire is of heavy gauge. An object of the invention accordingly is to provide a wire straightening apparatus which will avoid the above noted and other defects in prior apparatus.

To these ends and also to improve generally upon devices of this character, the invention consists in the various matters hereinafter described and claimed. In its broader aspects, the invention is not necessarily limited to the specific construction selected for illustrative purposes in the accompanying drawing in which

Fig. 1 is a side elevation of the apparatus.

Fig. 2 is a diagram.

Fig. 3 is an end elevation of Fig. 1 partly in section.

The numeral 2 indicates the frame of a conventional cold heading machine having feed rolls 4 and 6 for feeding wire W from a reel 8 to the heading dies. This is illustrative of any machine for feeding strip material. In front of the main frame is an auxiliary frame 10 having lubricated ways 12 for a carriage or slide 14 which carries the wire straightening apparatus. Journalled in the carriage are lower straightening rolls 16 and an upper straightening roll 18 the latter being adjustable by a screw 20. Also on the carriage are feed rolls 22 and 24 which grip the wire, the lower roll 22 at least being driven and the upper roll 24 having a releasing mechanism 26.

Projecting downwardly from the carriage is a bracket 28 supporting an electric motor M having a sprocket wheel driving a sprocket chain 30 leading to a sprocket wheel 32 on the shaft of the feed roll 22. If desired, the upper roll may also be geared to the shaft and the direction of rotation of the rolls is indicated by the arrows. The carriage has switch operating screws 34 and 36, the former being arranged to close a nor-

mally open switch 38 and the latter being arranged to open a normally closed switch 40.

As indicated in the diagram, the normally closed switch 40 is wired to a coil 42 and the normally open switch 38 is wired to a ground 44. The coil 42, when energized by closing of the switch 38, closes a normally open four-pole switch 46 which will start the motor M. An upper blade 48 on this switch is connected to a ground 50 to provide a holding circuit for the coil 42 after the switch 38 opens.

Assuming the intermittently operating header feed rolls 4 and 6 or other instrumentalities have pulled the carriage or slide 14 to the right hand limit, the screw 34 will close the switch 38 thereby energizing the coil 42 and closing the switch 46 to start the motor M. The motor then drives the rolls 22 and 24 which grip the wire and the carriage pulls itself along by the wire to the left hand limit of travel, the straightening rolls ironing out the kinks and bends. The screw 36 ultimately opens the switch 40 which breaks the holding circuit through the coil 42 and the switch 46 opens to stop the motor. Thereafter the carriage floats or slides to the right again with the wire as the wire is pulled forward by the heading machine.

The straightening apparatus straightens the wire without putting any load on the heading machine rolls 4 and 6 as occurs when a straightening apparatus is fixed in position and the heading machine must not only advance the wire to the heading dies but must also pull the wire through the straightener. The rolls of the present heading machine will have at most only the intermittent extra but light load of pulling the carriage to the right along its lubricated ways. The rolls thus escape the heavy load of straightening the wire and this insures a more reliable feed of the wire to the heading dies and more uniform work. The stiff wire, whether advancing or stationary, is always in the grip of the header feed rolls and furnishes the resistance upon which the feed rolls of the carriage operate to slide the carriage. The surface speed of the feed rolls of the carriage is at least as great as the total advance of the wire and, under some conditions, the carriage may have movement to the left with respect to the wire at about the same speed as the wire is being intermittently advanced by the heading machine. The heading machine will then go through numerous cycles while the carriage travels to the left hand limit switch.

I claim:

1. In combination with a machine having wire

feeding means, a carriage, a wire straightening device on the carriage, and power operated mechanism independent of the wire feeding means and reacting on the wire as it is engaged by the wire feeding means for shifting the carriage and the straightening device with respect to the wire.

2. In combination with a machine having wire feeding means, a carriage, a wire straightening device on the carriage, and driven feed rolls on the carriage adjacent to the straightening device and gripping the wire between them for shifting the carriage with respect to the wire.

3. In combination with a machine having wire feeding means, a carriage, wire straightening rolls journaled on the carriage, and driven feed rolls on the carriage and gripping the wire between them for shifting the carriage and the straightening rolls with respect to the wire.

4. In combination with a machine having wire feeding means, a carriage, a wire straightening device on the carriage, a motor mounted on the carriage, and feed rolls engaging the wire and driven by the motor to shift the carriage and the straightening device with respect to the wire.

5. In combination with a machine having wire feeding means, a carriage, a wire straightening device on the carriage, a motor mounted on the carriage, feed rolls engaging the wire and driven by the motor, and a pair of limit switches in the path of the carriage for starting the motor at one limit of travel and stopping it at another limit.

6. In combination with a machine having wire feeding means, a carriage shiftable towards and from the feeding means, a wire straightening device on the shiftable carriage, rolls on the carriage for gripping the wire between them, driving means for driving the rolls to cause the carriage to pull itself and the straightening device along the wire in a direction away from the wire feeding means, and means for stopping the roll driving means to cause the carriage to return with the advancing wire.

7. In combination with a machine having wire feeding means, a carriage shiftable towards and from the feeding means, a wire straightening device on the carriage, means on the carriage for gripping the wire, mechanism for actuating the gripping means to shift the carriage away from the wire feed means, and means for stopping the actuating mechanism to cause the carriage to return with the advancing wire.

10. 8. In combination with a machine having wire feeding means, a carriage shiftable towards and from the feeding means, a wire straightening device on the carriage, and mechanism for causing the carriage to travel along the wire in one direction and with the wire in the opposite direction.

9. In combination with a machine having wire feeding means, a wire straightening device engaging the wire and movable with respect to the wire feeding means, and means adjacent to the wire straightening device and reacting on the wire for causing the wire straightening device to travel along the wire in a direction away from the feeding means.

20. 10. In combination with a machine having wire feeding means, a wire straightening device engaging the wire, and power operated mechanism independent of the wire feeding means and reacting on the wire as it is engaged by the feeding means for operating the straightening device without adding to the load on the wire feeding means in feeding the wire.

30. 11. In combination with a machine having wire feeding means, a wire straightening device engaging the wire, and mechanism for operating the straightening device without adding to the load on the feeding means, said mechanism comprising a pair of driven rolls gripping the wire for causing the straightening device to travel along the wire away from the feeding means.

CHARLES PATRICK NAEGELE.
